UNITED STATES PATENT OFFICE

102,781

DESIGN FOR AN ASHTRAY

Clarence P. Harrington, Indiana, Pa.

Application August 31, 1936, Serial No. 64,658

Term of patent 7 years

To whom it may concern:

Be it known that I, Clarence P. Harrington, a citizen of the United States and a resident of Indiana, in the county of Indiana and State of Pennsylvania, have invented a new, original, and ornamental Design for an Ashtray, of which the following is a specification, reference being had to the accompanying drawing, forming a part hereof.

In the drawing:

The figure is a perspective view of an ashtray showing my new design.

I claim:

The ornamental design for an ashtray, as shown.

CLARENCE P. HARRINGTON.
